[54] STEP ASSEMBLY FLEXIBLY MOUNTED

[57]

ABSTRACT

[76] Inventors: Peter Sidles, Jr., 31 Timberlake Trail, Oswego, Ill. 60543; Bernard J. Wulff, 1224 Johnston Dr., Aurora, Ill. 60506

A step assembly for a vehicle includes a cable supported step member that has retaining elements which function to prevent rotation of the step about the cable.
